J. Borton,

Coal Drill.

N° 76,704.

Patented Apr 14, 1868.

H. Clayton & Co.

United States Patent Office.

JO B BORTON, OF ANTRIM, OHIO, has invented a new and useful Machine for Undermining and Excavating Coal, and for this invention has been granted Letters Patent No. 76,704, dated April 14, 1868, copies and records of which are filed with the Commissioner of Patents, and may be examined when desired.

IMPROVED COAL-EXCAVATING MACHINE.

The Schedule referred to in these Letters Patent and making part of the same.

TO ALL WHOM IT MAY CONCERN:

Be it known that I, JO B BORTON, of Antrim, in the county of Guernsey, and in the State of Ohio, have invented a certain new and useful Machine for Undermining and Excavating Coal; and I do hereby declare that the following is a full, clear, and exact description thereof, reference being had to the accompanying drawings, and to the letters of reference marked thereon, in which—

Figure 1 is a side elevation.
Figure 2 is a section at the rear end, with the part removed.
Figure 3 is a top view of one of the friction-rollers on which the moving frame slides.
Figure 4 is a side view of said roller.
Figure 5 is an end view in front of the machine, with gearing to move it.
Figure 6 is a section of the post and arm and shaft for operating the picks, and ratchet-wheel for moving the bed or machinery forward and back.

The nature of my invention consists in constructing a machine with a double motion, forward and backward operating-picks for coal-mining purposes, as hereinafter described and set forth.

To enable others skilled in the art to make and use my invention, I will proceed to describe its construction and operation.

In the construction of my invention, I form a stout frame, rather longer than wide, A A A. To the ends of this frame is attached a rack, A', fig. 2, into which a cog-wheel, T, in fig. 5, operates, and which is on a shaft passing through the lengthway of frame B, and which is placed directly above and rests on frame A. On the long sides of frame B are also racks, B', and pulley-rollers e e to lessen friction. This frame B is made to traverse across the frame A, by means of the rack A' and cog-wheel T, to move the machine up to the mine or coal as it is cut into by the picks M'. While this motion is being thus given to the machine, the frame C, to which frame all the other machinery is attached, is moved in the other direction, and lengthway of the frame A, by the cog-wheel S, on the same shaft as ratchet-wheel R, fig. 1, which is turned by the ratchet, o, and gear-wheel D. D are uprights set into frame C, as the bearings of the shafts G and H. The shaft G is a crank-shaft, to which is attached the driving-wheel F, fig. 1, to which the power is applied, also cog-gear wheel K and connecting-rod N, when steam is applied, or a band may be applied to the band-wheel F. On shaft H is another gear-wheel, which gears into wheel K, giving to N its motion. On this shaft are attached two cams c c, intended to operate the pickers M' M' by means of the sledges M M, against which they strike as the shaft H revolves. Attached also to this shaft is a cam-roller, a', which, as the said shaft revolves, strikes against the arm I' of upright post I, to which is attached the semicircle bearing a, for a connecting-wire, b, which wire is also attached to an arm extending from shaft b'; to which is also attached upright shaft P; which connects with ratchet-pawl O, and which turns the ratchet-wheel R to move frame C forward. d d are short uprights as guides to the pickers M' M'; L, the crank; u, a crank attached to the shaft, on which is placed the cog-wheel T, at the front end of the machine, for operating the said wheel, and moving the frames B and C up to the coal-mine, and three small wheels, on which the machine rests, and intended to assist in moving the same when desired so to do. N' is a slotted upright attached to the frame A as a guide to the pitman N. This pitman is made of two pieces, one having a slot of several inches or more in length, and held together by a screw and nut, so that it can be lengthened or shortened, as may be desired, in applying it to the engine, as the machine moves from or to the engine in operating on the mine.

In the operation of my invention, the machine is placed close to the bed of coal to be mined; and in order to facilitate the movement of the machine up toward the coal, or lengthways of the mine, I may lay a temporary railroad both ways, on which the machine is set, or it may rest with wheels, 1, 2, 3, and 4, on the ground. If steam is used, the pitman is attached to the crank of the engine, and power is communicated to the machine by the crank-shaft G, and the operation will be the same as when hand-power is applied to the crank, L. When the crank, L, is turned by hand, motion is given to the shaft G, causing gear-wheel K to revolve, which operates

on driving-wheel I^2 , causing shaft H to revolve, which causes the cams c c alternately to operate on the sledges M M , which are hung on shafts g g , which presses down the upper ends of the arms of the sledges, thus raising the same sufficiently high to allow a force of from twenty to fifty pounds or more to fall against the ends of chisels M' M' , thus forcing them into the coal, cutting at every blow further and further into the coal, cutting the body thereof into grooves of depths and spaces apart to leave the bed cut in blocks, which will be easily broken off and removed. As the chisels are driven forward by each blow from the falling of the sledges, the chisels are thrown back by means of the spiral springs d' , in fig. 2, in position to receive another blow from the sledge.

If desired to make the chisel operate oftener, I increase the number of the cams c on the shaft H . When I begin to operate, the machine is run back as far as will allow, still keeping the cog-wheel S in the cogs of the ratchet B ; and as the shaft H revolves, the cam-roller a' , in fig. 1, operates on the under side of the arm I' , raising it up, and, by means of connecting-rod b , raises an arm, shown in dotted lines in fig. 1, attached to shaft b' , to which is attached lever p , attached to pawl o , thus causing the pawl o , as it catches into ratchet-wheel R , to push said wheel around, thus turning cog-wheel S , and thus move the machine forward the length of the rack, the machine resting at the same time on the pulley-rollers e e to avoid friction. When the machine has run through, as described, it is drawn back, and is ready for another operation, as above.

When the lateral motion is to be given to the machine, in order to keep it up to its work in cutting a deep cut into the coal-bed, it is done by turning the crank u , which causes the cog-wheels T T to revolve on the rack A' , thus sliding up the machine laterally to the bed of coal as fast as the chisels cut into the same, and when it has cut in to suit, the machine is moved back in the same manner.

Thus it will be seen that I make a simple, and by no means a complex machine, having two motions, one parallel to the side of the mine, and one moving the machine directly up to the mine as fast as the pickers or chisels cut their way into the bed of coal both longitudinally and laterally—a machine, cheap and easily constructed, to be operated either by hand or steam-power.

Having thus fully described the nature of my invention, what I claim as new, and desire to secure by Letters Patent, is—

1. I claim the picks or chisels M' M' , sledges M M , and cams c c , operated by shaft H and wheel I , in combination as described, and operating as and for the purposes set forth.
2. I claim cam-roller a' on shaft H , adjustable arm I' , connecting-rod b , arms b' and p on rock-shaft b'' , pawl o , and ratchet-wheel R , in combination with cog-wheels S S , as described, and operating as and for the purposes set forth.
3. I claim, in combination with a mining-machine thus constructed, crank-shaft G , balance-wheel F , and gear-wheel K , pitman N , constructed and operating as described and set forth.
4. I claim the combination of the chisels or picks M' M' with the transversible frames B and C , carrying the intermediate devices, constructed as described, and operating as set forth.

In testimony that I claim the above-described invention, I have hereunto signed my name, this day of November, 1867.

JOB BORTON.
